PUMP

George William Rawlings, Park Hill,
Kenilworth, EnglandApplication July 10, 1935, Serial No. 30,606
In Great Britain December 14, 1934

3 Claims. (Cl. 103—44)

This invention has reference to improvements relating to pumps and is concerned more particularly with pumps of the kind described in the specification of my abandoned application Serial No. 751,055 filed 1st November 1934 in which the pumping effort is engendered by stressing a tube as by flexing, bending or twisting so as to produce a change in cross sectional area without substantial change in the mean length whereby 5 the contained volume of the tube is alternately increased and decreased or is alternately increased or decreased and restored to its initial volume.

With pumps of the said kind it is found that 10 when used for delivering liquid at relatively high pressures and under the same conditions of operation a constant volume of delivery for each pumping cycle is not attained owing to the compression of the liquid or of air which may have entered the tube or of air occluded within the 15 liquid. As a consequence pumps of this kind have not been very successful when utilized for the injection of liquid fuel for direct fuel injection internal combustion engines and the present invention has for its primary object the provision 20 of an improved liquid pump which retains the simplicity of pumps of the kind under review but which at the same time ensures the delivery of constant volumes of liquid at each pumping cycle 25 under the same conditions of operation.

A further object of the invention is the provision of means which ensures an abrupt termination 30 to the discharge thereby rendering the pump particularly suitable for the injection of fuel in internal combustion engines of the direct fuel injection type.

The invention consists of an improved pump comprising a tube, means for effecting an alternate flexing, bending or twisting of the said tube 35 so as to engender a pumping effort by varying the contained volume of the bore of said tube, a pumping chamber, a pump body having therein a passage placing the said chamber in communication with a source of supply and with a discharge 40 line and with an orifice opening into the pumping chamber, valve means for controlling the supply of liquid to said passage and the discharge of liquid therefrom, a mercury filling for said tube, free from air, a resilient diaphragm dividing 45 the aforesaid pumping chamber from the tube and consequently from the adjacent end of the mercury column, said diaphragm normally occupying a position in which the volume of the pumping chamber is slightly in excess of the 50 maximum volume of liquid required to be ejected 55

at a delivery operation and under the influence of the pressure generated in the tube, closing the aforesaid orifice.

The invention will now be described with particular reference to the accompanying sheets of 5 drawings which illustrate the invention in its application to a liquid fuel injection pump for use with an internal combustion engine of the direct fuel injection type.

In the drawings:—

Figure 1 is a vertical section of the improved pump.

Figure 2 is a composite fragmentary view illustrating diagrammatically the position occupied by the parts immediately prior to injection, the 15 portion of the pump containing the diaphragm referred to hereinbefore being shown on an enlarged scale.

Figure 3 is a similar view to Figure 2 but showing the positions occupied by the parts at the 20 completion of an injection.

As illustrated in the drawings, the improved injection pump comprises a curved metal walled tube 4 of an elliptical shape in cross section, said tube being closed at one end and having pivotal 25 connection adjacent to this closed end to the outer end of a lever 5 which is fulcrumed adjacent to its other end on a ball bearing race 6 which is mounted on a fixed spindle 7. This lever 20 is provided intermediate the ends with a projection 5a which co-operates with a cam 8 mounted on a shaft 9 adapted to be rotated by the engine. The other end of the tube 4 to that mentioned terminates in an enlarged portion 4a having 30 therein a centrally disposed aperture which 35 communicates with the bore in the tube 4 the said aperture being closed by a removable plug 10.

The bore in the enlarged portion 4a has communication by way of a passage 4b with an inclined passage 11a formed in a body 11 supported from 40 the base 12 of the pump said passage 11a opening into a chamber 11b. The body 11 is provided with a cylindrical recess which is symmetrically disposed relatively to the chamber 11b but of greater diameter. The walls of the cylindrical 45 recess are tapped for the reception of a block 13 having therein a vertically disposed passage 13a. This passage 13a communicates by way of a one-way valve 14 with a passage leading to the discharge line 15 from a pump, hereinafter termed 50 the primary pump, which is not shown but which is generally similar to the injection pump illustrated hereinbefore and which primary pump delivers fuel from a reservoir to the aforesaid injection pump. The liquid is supplied to the in- 55

jection pump through a nozzle 16 which has a discharge orifice having a known coefficient of discharge so that by varying the pressure of the supply as delivered by the primary pump the quantity of fuel supplied to the present pump can be controlled. The passage 13^a has communication under the control of a one-way valve 17 with the discharge pipe 18 leading to the fuel injector not shown.

10 The pumping chamber 11^b is divided into two parts by a dished spring steel diaphragm 19 and the upper part of the said chamber 11^b is termed hereinafter the pumping chamber 11^c.

15 The lower part of the chamber 11^b, the passage 11^a, 4^b and the bore of the tube 4 are filled with mercury which is freed from air.

20 The volume of the pumping chamber 11^c is slightly greater than the maximum quantity of liquid which is capable of being delivered at a pumping cycle.

25 The operation of the pump as shown in the accompanying drawings is as follows:—

30 Liquid is supplied at a controllable pressure by the primary pump to the pumping chamber 11^c by way of the nozzle 16, the one way valve 14 and the passage 13^a. The liquid is admitted to the pumping chamber 11^c during that part of the cycle when the engine driven shaft 9 is rotating the cam 8 from the initial position shown in Figure 3 to that shown in Figure 2. During this admission period the tube 4 is flexed by the lever 5 in such a manner that its contained volume is increased thus permitting the diaphragm 19 to assume the position shown in Figure 2 and thus providing capacity for the inlet of fluid to the pumping chamber 11^c.

35 The quantity of fluid supplied to the pumping chamber 11^c during this admission period depends not only upon the capacity so provided but also upon the pressure maintained by the primary pump and the coefficient of discharge of the nozzle 16. When the further rotation of the shaft 9 completes the revolution and brings the cam 8 to the initial position shown in Figures 45 1 and 3 the tube 4 is permitted to resume its initial form whereupon its contained volume is decreased and the diaphragm 19 is subjected to the consequent pressure of the mercury filling and is thereby constrained to eject the liquid from the chamber 11^c, this ejection continuing until the diaphragm 19 abuts the face of the block 13 as shown in Figure 3 whereupon the ejection terminates abruptly. This ejection of the liquid from the pumping chamber 11^c is of course the injection of fuel to the engine.

40 It will be appreciated that under any given conditions of working constant quantities of liquid are supplied to the injection pump and that constant quantities of liquid are forced by the injection pump to the fuel injector.

45 The tube 4 may be filled with liquids having a high bulk modulus other than mercury or with a plastic material provided of course that the liquid or plastic material employed is not subject to any

50 solvent or other undesirable action with the medium being pumped.

55 In a modification not illustrated a flat diaphragm 19 may be employed and the lower end of the block 13 given a concave formation.

60 It will be obvious that a battery of pumps may be operated from a common engine driven shaft 9.

65 What I claim is:—

1. A pump comprising a tube, means for effecting an alternate flexing, bending or twisting of the said tube so as to engender a pumping effort by varying the contained volume of the bore of said tube, a pumping chamber, a pump body having therein a passage placing the said chamber in communication with a source of supply and with a discharge line and with an orifice opening into the pumping chamber, valve means for controlling the supply of liquid to said passage and the discharge of liquid therefrom, a mercury filling 20 for said tube free from air, a resilient diaphragm dividing the pump chamber into two parts one of which is in communication by way of the aforesaid orifice with the passage in the pump body and the other part of which is in communication with the tube and is filled with mercury, said diaphragm normally occupying the position in which the volume of the pumping chamber is slightly in excess of the maximum volume of liquid required to be ejected at a delivery operation and under the influence of the pressure generated in the tube closing the aforesaid orifice to effect an abrupt termination of a discharge operation.

2. A pump comprising a tube, a power source, means driven from said power source for periodically bending the tube so as to engender a pumping effort by varying the contained volume of the bore of said tube, a pump body, a pumping chamber formed in said pump body, a plug adapted to fit within said body and having therein a passage placing the pumping chamber in communication with a source of supply and with a discharge line and with an orifice opening into the pumping chamber, valve means for controlling the supply of liquid to said passage and the discharge of liquid therefrom, a mercury filling for said tube, and a resilient sheet steel diaphragm dividing the aforesaid pumping chamber into two parts one of which is in communication by way of the aforesaid orifice with the passage in the plug and the other of which is in communication with the tube and is filled by mercury, said diaphragm normally occupying the position in which the volume of the pumping chamber is slightly in excess of the maximum volume of liquid required to be ejected at a delivery and under the influence of the pressure generated in the tube closing with a snap action the aforesaid orifice in order to effect an abrupt termination of the discharge.

3. A pump, according to claim 2, wherein the diaphragm is dished and co-acts with the flat end of the plug for the purpose of enhancing the speed of closure of the orifice by the diaphragm.

60 GEORGE WILLIAM RAWLINGS.
